UNITED STATES PATENT OFFICE.

EDWARD H. AMET, OF WAUKEGAN, ILLINOIS.

AUTOMATIC BRAKE AND TAKE-UP DEVICE FOR TROLLEY-CORDS.

SPECIFICATION forming part of Letters Patent No. 768,260, dated August 23, 1904.

Application filed June 6, 1904. Serial No. 211,314. (No model.)

To all whom it may concern:

Be it known that I, EDWARD H. AMET, a citizen of the United States, residing at Waukegan, in the county of Lake and State of Illinois, have invented certain new and useful Improvements in Automatic Brake and Take-Up Devices for Trolley-Cords, of which the following is a specification.

This invention relates to an automatic brake and take-up device for trolley-cords, and has among its salient objects to provide a device to which the free or lower end of a trolley-cord can be attached and which operates to keep said cord taut during the movement of the trolley along the trolley-wire, to provide a device of the character referred to which operates automatically to lock said trolley-cord against paying out the instant the trolley leaves the wire, thereby preventing the trolley-pole from rising under the tension of its spring and coming into damaging engagement with the wire and cross-wires of the system, and to provide a simple, effective, and cheap device of the character referred to.

To the above ends the invention consists in the matters hereinafter set forth and will be readily understood from the following description, reference being had to the accompanying drawings, illustrating one embodiment of the invention, and in which—

Figure 1 is a fragmentary side elevation of a car and trolley-pole with the invention applied thereto. Fig. 2 is a front elevation of the invention with the casing cut away, and Fig. 3 is a sectional view taken transversely on a vertical line through the invention.

Referring to the drawings, 1 designates a trolley-cord attached at one end to a trolley-pole and at the other end to an automatic brake and take-up device constituting the present invention and designated as a whole 2, said device comprising a back 3 and a cover 4, mounted upon said back, together with internal mechanism, and all mounted upon the car in the manner indicated in Fig. 1.

5 designates a hollow drum member mounted upon the back 3 by means of a bolt 6 and provided on the rear edge of its periphery with a series of ratchet-teeth 7, in the middle 50 of its periphery with a trolley-cord-receiving

groove 8, and on the outer edge of its periphery with a smooth bearing-surface 9. Mounted within said drum is a coiled spring 10, secured at one end to the wall of the drum and at its other end to the bolt 6, upon which said drum revolves. The trolley-cord 1 enters the casing of the device through an aperture 11 in the upper wall and passes around said drum in the groove 8 in the direction of the rotation of the drum under the tension of the spring 10, said spring tending to wind up the trolley-cord about the drum.

12 designates a pawl pivotally mounted at 13 upon the back member 3 just above the drum 5. The longer end of the pawl is arranged to fit the notches in the drum formed by the teeth 7 when said pawl is rocked upon its pivot, while the shorter end carries a roller 14, revolvably mounted thereon and provided with a circumferentially-extending groove 15 in alignment with the groove 8 around the drum. The outer edge of said roller is in the present instance provided with a smooth bearing-surface 15', arranged to move upon the bearing-surface 9 of the drum 5. 16 designates a stationary block member secured to the back 3 above said pawl and provided at one end with an eyelet 17, through which the trolley-cord is passed and which at its other end supports a coiled spring 18, secured at one end to the pawl 12 and at the other end adjustably to the block by means of a thumb-nut 19. The tension of the spring 18 is in a sense opposed to the tension of the coiled spring 10 and accordingly is adjusted so as to barely hold the end of the pawl out of engagement with the drum during the normal operation of the trolley—that is to say, the tension on the cord passing in an indirect line around the roller tends to throw the pawl into engagement with the drum, while the spring 18 is so adjusted as to hold it out of engagement. When thus adjusted, if the trolley suddenly jumps the wire the sudden increased tension on the trolley-cord combined with the inertia of the drum and the action of the coiled spring 10 thereof overcomes the tension of the spring 18 and instantly throws the pawl into engagement with the ratchet-teeth of the drum, and once it has been thrown into

engagement in this manner the frictional engagement of the teeth with the end of the pawl or dogging device is sufficient to hold it from being lifted out by the spring 18. It will thus be seen that the instant the trolley leaves the wire and starts upward under the tension of the spring it simultaneously moves the pawl into locking engagement with the drum and prevents the pole from rising any appreciable distance, and thereby prevents the damage usually done by the pole striking the wires overhead. The spring 18, which holds the pawl, is so adjusted that the gradual and uniform movements of the trolley up and down in its travel along the trolley-wire does not lock it, while the spring in the drum keeps the trolley-cord stretched taut at all times and makes a quick response of the pawl possible when the trolley accidentally gets off the wire, and the pole rises under the tension of its spring *a*, which is of course stronger than the spring 18, which holds the long end of the pawl 12 out of engagement with the drum.

It is obvious that changes and modifications can be made in the details of construction and arrangement without departing from the spirit of the invention, and I do not, therefore, limit the invention to the details shown and described except in so far as they are made the subject-matter of specific claims.

I claim—

1. An automatic brake and take-up device for trolley-cords, comprising an automatic take-up mechanism mounted upon a suitable support and with which the trolley-cord is operatively connected, a dogging mechanism movably mounted and having a part engaging the trolley-cord and holding the latter deflected out of a direct line of draft upon said dogging mechanism and provided also with a locking part adapted to directly engage and lock the take-up mechanism against paying-out movement, and means yieldingly holding the locking member of said dogging mechanism out of locking engagement with the take-up mechanism.
2. An automatic brake and take-up device for trolley-cords, comprising a support, a spring-actuated member revolvably mounted upon said support and around which said cord is wound, a pawl pivotally mounted upon said support adjacent said spring-actuated member, said pawl having yielding engagement at one end with the trolley-cord and adapted to be moved into locking engagement with said spring-actuated member at its other end si-

multaneously with any sudden increase of tension upon said cord, for the purpose described.

3. In an automatic brake and take-up device for trolley-cords, the combination with a suitable casing therefor mounted upon the car, of a spring-actuated member revolvably mounted within said casing and around which said cord is wound, said spring tending to keep said cord stretched taut at all times, a pawl pivotally mounted within said casing and adapted to be moved into locking engagement with said spring-actuated member to prevent the paying out of said trolley-cord, a roller mounted upon said pawl and moving upon said cord to actuate said pawl, said roller being so positioned that sudden increase in the tension upon said cord operates to move said pawl into locking engagement with said spring-actuated member, for the purpose described.

4. In an automatic brake and take-up device for trolley-cords, the combination with a suitable casing therefor, of a spring-actuated take-up member revolvably mounted within said casing and provided on its periphery with ratchet-teeth and a cord-receiving groove, a locking-pawl pivotally mounted within said casing and adapted to be moved into locking engagement with said take-up member to prevent the paying out of said cord, a roller revolvably mounted upon one end of said pawl and around which said cord passes, a spring holding said pawl yieldingly out of engagement with said take-up member and said roller into engagement with said cord, said roller and said pawl being so positioned that a sudden increase in the tension upon said cord operates automatically to move said pawl into locking engagement with said take-up member, substantially in the manner and for the purpose described.

5. An automatic brake and take-up device for trolley-cords, comprising a spring take-up mechanism mounted upon a suitable support and with which the trolley-cord is operatively connected, a dogging device movably mounted adjacent to the trolley-cord and holding the latter deflected out of a direct line of draft upon the take-up mechanism and having a pawl portion adapted to engage and lock the take-up mechanism, and a spring yieldingly holding the pawl out of engagement with the take-up mechanism.

EDWARD H. AMET.
